Inventor:

Fred Arn,

By Special Appointment Donaldson & Hall
Attys.

UNITED STATES PATENT OFFICE.

FRED ARN, OF CHATTANOOGA, TENNESSEE, ASSIGNOR TO J. M. CARD LUMBER CO., OF CHATTANOOGA, TENNESSEE, A CORPORATION OF TENNESSEE.

CHOCK-BLOCK FOR AUTOMOBILES.

1,400,735.

Specification of Letters Patent. Patented Dec. 20, 1921.

Application filed August 23, 1919. Serial No. 319,362.

To all whom it may concern:

Be it known that I, FRED ARN, a citizen of the United States, and resident of Chattanooga, Tennessee, have invented certain new and useful Improvements in Chock-Blocks for Automobiles, of which the following is a specification.

My invention is designed to provide a chock block which may be manufactured economically both as to the material used and the time expended in severing the blocks from a piece of timber and in their formation to the desired shape.

In the accompanying drawings—

Figure 1 is a side view of a chock block embodying my invention and

Fig. 2 is a perspective view.

The block is formed of a single piece of wood having a front face which conforms in curve to the general peripheral curve of the wheel and having in this curve face a groove conforming to the substantially cylindrical shape of the tire. The block has parallel side faces and it has an extended heel portion at 2. This is formed by cutting the rear face on an incline and in one plane from the top to the bottom of the block and the plane upon which this incline is formed is the diagonal of an oblong of which the height corresponds to the height of the block and the width corresponds to the distance between the upper rear edge of the block and a vertical plane extending up from the rear lower edge of the extended heel. This incline is such that when the piece from which the block is formed is severed on this incline from the piece of timber, the incline face left at the end of the piece of timber will provide the extended heel portion of the next block. In other words, the same cut which severs the block from the piece of timber provides the two incline faces which form the extended heels of the two blocks successively cut from the timber. This extended heel presents the advantage that a surface is provided which will readily receive the nails for attaching the block to the platform of the car or the storage house in which the automobiles are carried or stored, it being possible to insert the nails with greater ease and facility in this inclined rear face rather than in a vertical rear face. Furthermore, this rearwardly inclined heel extension provides a bearing on the floor at a considerable

distance beyond the bearing face of the block so that there will be no danger of the block tipping over if an automobile is brought against it with considerable force, and thus the nails will not be strained and will not be drawn from the platform and the block dislodged.

Besides the advantage above pointed out, of presenting an inclined surface which is well adapted to receive the nails, and also of presenting a bearing well in the rear of and at a considerable distance from the point where the tire bears upon the block, the additional advantage of economy in manufacture is presented, because the same inclined straight cut which severs the block from the timber also has the effect of forming the rear face of the severed block and also the rear face of the next block to be cut from the timber.

Referring to the adaptability of the inclined rear face for receiving the nails, it may be further pointed out that the nearer the nails are positioned perpendicularly to the floor of the car or other support to which the blocks are to be affixed, the better will the nails hold against the strain to which the blocks are subjected. A applicant's inclined rear face enables the nail to be set substantially perpendicular to the car floor or receiving surface, and at the same time the head of the nail is freely accessible for the hammer blows to be applied thereto, because it will be noticed, that the rear inclined face slopes upwardly and away from the vertical plane in which the nail is positioned. This is not true, however, in a construction having a vertical rear face, because the nail would in the latter case have to be placed at a considerable inclination to the rear face and to the floor of the car in order to enable it to be driven into place.

I claim as my invention:

A chock block for automobiles formed of a solid piece of wood having a base portion, a curved front bearing face extending from the top of the block to the bottom supporting face of the base portion and a rearwardly extended heel inclining in one plane downwardly and backwardly from the upper to the lower face of the block, substantially as described.

In testimony whereof, I affix my signature.

FRED ARN.
